[57] **CLAIM**

The ornamental design for a foot engagable mobile board, as shown and described.

DESCRIPTION

FIG. 1 is a front prospective view of a foot engagable mobile board according to the present invention;

FIG. 2 is a top plan view;

FIG. 3 is a left side elevational view, the right side elevational view being a mirror image thereof;

FIG. 4 is a front elevational view;

FIG. 5 is a rear elevational view; and,

FIG. 6 is a bottom plan view.

The phantom line representation in FIG. 3 does not comprise a part of the present invention.
